UNITED STATES PATENT OFFICE

RAY S. SMITH, OF MODESTO, CALIFORNIA

GOLF TEE CONTAINER AND RETRIEVER

Application filed August 17, 1929. Serial No. 386,613.

This invention relates to golfing accessories, my principal object being to provide a device adapted to be carried in a pocket of the player designed to serve two ends—to 5 form both an anchor for the tee being used during the playing of the game and as a container for such tee between periods of use; and also to carry a reserve supply of tees for use if necessary at any time.

10 One common annoyance incident to the playing of the game—the loss of the tee due to its being carried away from the tee-off ground some distance with the hitting of the ball—is eliminated; and should such tee be 15 broken or damaged at any time, as is frequently the case, another one is directly at hand to be used thereafter.

A further object of the invention is to produce a simple and inexpensive device and yet 20 one which will be exceedingly effective for the purpose for which it is designed.

These objects I accomplish by means of such structure and relative arrangement of parts as will fully appear by a perusal of 25 the following specification and claim.

In the drawings similar characters of reference indicate corresponding parts in the several views:

Fig. 1 is a perspective view showing my 30 improved device as in operation.

Fig. 2 is a perspective view of the container opened.

Fig. 3 is a longitudinal section of the same.

Fig. 4 is a perspective view of a modified 35 form of container.

Referring now more particularly to the characters of reference on the drawings, and particularly at present to Figs. 1 to 3, the device comprises a relatively small oblong box 40 or receptacle 1 of suitable dimensions having a hinged lid. The box is preferably divided into two longitudinally separated compartments 3 and 4 by a transverse partition 5 having a hinged lid 6 thereon independent of the lid 2, to cover the compartment 3. The compartment is intended to hold a number of reserve tees, which in the present instance are shown as being of the rubber cup type 7 adapted to nest into each other. This compartment may also contain the service tee 7a

actually being employed during the game in teeing up the ball between periods of use. The compartment 3 may be used to hold toilet accessories or other articles, or it may also be used to receive the service tee when 55 the same is not in use, as may be desired by the player.

Mounted in the box under the compartment 3 is a horizontally disposed spring rotated reel 8 of standard form about which a flexible cord 9 is wound. One end of this cord is attached to the wheel while the other end projects through a hole 10 in the adjacent end of the box and is secured to the service tee 7a. The reel is of that common type in 60 which an unwinding pull on the cord causes the reel to rotate and the spring thereof to be compressed; the spring then remaining compressed until it is released, to turn the reel in the opposite direction and wind the 65 cord thereon by the depression of a button 11 projecting slightly from the bottom of the box. When the tee is not in use it is placed in its compartment in the box and the majority of the cord is wound on the reel; that 70 portion of the cord which extends from the opening 10 to the top of the box being enclosed in a vertical groove 12 formed in the end of the box on the outside thereof and extending from said opening to the top of the 75 box. When it is desired to use the tee it is only necessary to open the box, remove the tee, and draw the cord out the desired distance so that the box may rest on the ground 80 out of the way of the club addressing the ball 13 supported by the tee. The box in that case then serves as an anchor for the service tee, preventing the same from being displaced to any extent from its position on 85 the ground. 90

It is to be understood that while I have shown a standard form of tee any other form suitable for the purpose may of course be used instead.

In the type of device shown in Fig. 4 the box 1a only has one compartment to receive both the service and reserve tees and the spring reel 8a is mounted in a vertical position in the box at one end of the same as 95 100

shown, with its control button 11a projecting from said end.

From the foregoing description it will be readily seen that I have produced such a device as substantially fulfills the objects of the invention as set forth herein.

While this specification sets forth in detail the present and preferred construction of the device, still in practice such deviations 10 from such detail may be resorted to as do not form a departure from the spirit of the invention, as defined by the appended claim.

Having thus described my invention what I claim as new and useful and desire to set 15 cure by Letters Patent is:

A golf tee holder comprising an open-topped container, a lid for the same, a spring reel in the container, a cord wound on the reel and projecting thence through an opening 20 in the side of the container, a tee on the outer end of the cord, the outer surface of the container having a depression at the top in vertical alignment with the opening to receive the portion of the cord adjacent the 25 tee when the latter is placed in the container and prevent pinching of the cord by the lid when the latter is in a closed position.

In testimony whereof I affix my signature.
RAY S. SMITH.
